US00D616700S

(12) **United States Design Patent**
Pourounidis et al.

(10) **Patent No.:** US D616,700 S
(45) **Date of Patent:** ** Jun. 1, 2010

(54) **TING CUTTING BOARD**

(76) Inventors: **Harry Pourounidis**, C/-BAMBIS, 1-9 Moreland Road East Coburg, Victoria, 3058 (AU); **Curtis Stone**, C/-BAMBIS, 1-9 Moreland Road East Coburg, Victoria, 3058 (AU)

(**) Term: **14 Years**

(21) Appl. No.: **29/298,281**

(22) Filed: **Nov. 30, 2007**

(30) **Foreign Application Priority Data**

Jun. 1, 2007 (AU) 18241/2007

(51) **LOC (9) Cl.** 07-04

(52) **U.S. Cl.** D7/388; D7/698

(58) **Field of Classification Search** 269/13, 269/16, 289 R, 15, 302; 241/273.2; 99/446; D7/388, 698, 543, 669; D9/527; D32/56; D12/425; D6/406.2, 406.4, 510, 511; 30/151, 30/298; 296/15, 302; 108/156

See application file for complete search history.
